UNITED STATES PATENT OFFICE.

NATHAN ULLMAN, OF NEW YORK, N. Y.

DESIGN FOR A TOY PAINTING OUTFIT.

58,119.

Specification for Design.

Patented June 7, 1921.

Application filed March 16, 1921. Serial No. 452,768. Term of patent 7 years.

To all whom it may concern:

Be it known that I, NATHAN ULLMAN, a citizen of the United States, residing in the city of New York, in the county of New York and State of New York, have invented a new, original, and ornamental Design for a Toy Painting Outfit, of which the following is a specification, reference being had to the accompanying drawing, forming part thereof.

The figure is a perspective of a toy painting outfit, showing my new design.

I claim:

The ornamental design for a toy painting outfit, as shown.

NATHAN ULLMAN.
